Primary Examiner — John Windmuller(74) *Attorney, Agent, or Firm* — John Maldjian; Maldjian Law Group LLC(57) **CLAIM**

The ornamental design for a step clip fastening system, as shown and described.

DESCRIPTION

FIG. 1 is a front, top and right side perspective view of a step clip fastening system showing my new design;

FIG. 2 is an enlarged partial view of the front, top and right side perspective view thereof;

FIG. 3 is a front plan view thereof;

FIG. 4 is a left view thereof;

FIG. 5 is an enlarged partial view of a front, right side view thereof; and,

FIG. 6 is an enlarged partial view of a front, left side view thereof.
